UNITED STATES PATENT OFFICE

169,901

ICE-CREAM CONE DISPENSER

Max Goldberg, Glencoe, Ill.

Application February 8, 1952, Serial No. 18,446

Term of patent 3½ years

(Cl. D52—2)

To all whom it may concern:

Be it known that I, Max Goldberg, a citizen of the United States, residing at Glencoe, county of Cook and State of Illinois, have invented a new, original, and ornamental Design for an Ice-Cream Cone Dispenser, of which the following is a specification, reference being had to the accompanying drawings, forming a part thereof, in which—

Figure 1 is a front perspective view of an ice-cream cone dispenser showing my new design;

Figure 2 is a top plan view thereof;

Figure 3 is a side elevational view thereof;

Figure 4 is a front elevational view thereof; and

Figure 5 is an elevational view showing the side opposite that shown in Figure 3.

I claim:

The ornamental design for an ice-cream cone dispenser, as shown.

MAX GOLDBERG.
